UNITED STATES PATENT OFFICE

EDMUND W. ZEH, OF NEWARK, NEW JERSEY.

POWER-PRESS.

1,076,932.

Specification of Letters Patent.

Patented Oct. 28, 1913.

Application filed June 1, 1912. Serial No. 700,908.

To all whom it may concern:

Be it known that I, EDMUND W. ZEH, a citizen of the United States, residing at Newark, in the county of Essex and State of New Jersey, have invented certain Improvements in Power-Presses, of which the following is a specification.

This invention relates to that class of power presses in which a head for carrying the upper die is moved up and down by a screw and means for oppositely rotating said screw.

The objects of the invention are to secure improved tripping means by which the machine may be operated; to particularly provide means for effecting such tripping by the operator's foot; to enable the tripping mechanism to automatically operate to prevent a second blow of the hammer unless the operator manually depresses the treadle again, or on the other hand to cause continuous operation of the machine when so desired; to provide means for quickly changing from such continuous operation to single blows so that the hammer will become stationary at the end of its upstroke; to obtain improved means for automatically stopping the hammer at the end of its upstroke without undue oscillation; to make said means readily adjustable; to provide means for varying the force of impact for different kinds of work without changing the speed of the drive shaft; to secure simplicity of construction and operation, and to obtain other advantages and results as may be brought out in the following description.

Referring to the accompanying drawings, in which like numerals of reference indicate the same parts throughout the several figures, Figure 1 is a perspective view of my improved power press in idle position with the hammer up; Fig. 2 is a front view of a portion of the press with a certain tripping rod broken away and the treadle in normal position; Fig. 3 is a view similar to Fig. 2, showing the treadle depressed; Fig. 4 is a view similar to Fig. 2, but showing the tripping rod which was there broken away; Fig. 5 is a longitudinal sectional view through the upper end of said tripping rod; Fig. 6 is a front view of a certain brake as applied to the horizontal friction wheel, portions of the machine being broken away; and Fig. 7 is a plan view of the same,

and Fig. 8 is a detail section of the sliding head or hammer illustrating the use of a certain lengthening socket.

In the specific embodiment of the invention illustrated in said drawings, 1 indicates the frame of my improved press, preferably mounted upon legs 2, 2 to elevate it to a suitable and convenient height. Said frame 1 is centrally open, providing a vertical slideway for a head or hammer 3 carried upon the lower end of a screw 4 which works through the top of said frame 1, and has at its upper end above the same a horizontal wheel 5 providing at its periphery a friction surface. The said hammer 3 is adapted to carry at its lower end a die, not shown, and the frame 1 forms at the bottom of its central opening a bed 6 to receive the work or the lower die adapted to coöperate with the other die. In order to raise and lower the upper die to secure the necessary pressure or impact, the screw 4 is alternately rotated in opposite directions by the following means. Above the friction wheel 5 a horizontal shaft 7 extends diametrically of said wheel, and is journaled in brackets 8, 9 bolted to and projecting upward from the frame 1 at opposite sides of the machine. This shaft is provided at one end outside the bracket 8 with fast and loose pulleys 10 and 11 adapted to receive a driving belt (not shown) and which belt can be moved from one pulley or the other by the belt shifter 12. Between its bearings in the brackets 8, 9, said shaft 7 has fast upon itself driving disks 13 and 14 adapted to alternately engage at their inner facing sides diametrically opposite portions of the frictional rim of the horizontal wheel 5. Obviously, as one or the other of the said drive disks 13, 14 is engaged with the friction wheel 5, said friction wheel will be rotated in one direction or the other, and the screw 4 lowered or raised. To effect such alternate engagement of the drive disks 13, 14 with the friction wheel 5, the shaft 7 is slid longitudinally in its bearings in the brackets 8, 9 by the means next to be described.

Upon the end of the shaft 7 outside of the bracket 9 are two collars 15, 15 made fast by set screws or the like, and between said collars is a sleeve 16 rotatably loose upon the shaft and having trunnions 17 received by the forked end 18 of a lever 19 which is

fulcrumed as at 20, upon an arm 21 of the bracket 9, so as to swing in a plane through the shaft 7, and which plane is preferably vertical or substantially so. The lever 19 is 5 curved to bring its lower end into substantially horizontal position, and said lower end is connected pivotally to the upper end of a connecting rod 22. This connecting rod 22 has its lower end pivotally connected, 10 as at 23, to the arm 24 of a lever 25 which is normally horizontal, and which is pivoted upon the frame 1, or front of the bed 6 thereof, as at 26, to swing in a substantially vertical plane. The arm of this lever 25 opposite the arm 24 is provided with a handle 27 by means of which the lever can be swung to slide the drive-disk shaft 7, and so rotate the screw 4 in either direction to move the hammer head 3 up or down. Preferably 15 a weight 28 upon the arm 24 of the lever normally holds said arm 24 depressed, so as to engage the drive-disk 14 with the friction-wheel 5 and elevate the screw, and thus unless the handle 27 is positively forced 20 downward and held there, the sliding head 3 will move upward. To terminate this upward movement, I provide a brake shown in the drawings supported upon the shaft 7, but not revolving with said shaft. Preferably 25 such support is by means of a sleeve 29 loose on the shaft 7 and held against longitudinal sliding thereon by a collar 30 or the like, as best shown in Figs. 6 and 7. A brake shoe 31 of wood or any other suitable 30 material forms the engaging face of the brake, and it will be understood that the brake is so placed that as the friction wheel 5 is rotated and mounts upwardly, the upper surface of said wheel 5, 35 preferably adjacent to the periphery thereof, meets and rubs against the said brake shoe 31 and is thereby stopped. Preferably the free swinging end of the brake is connected by a link 32 to the horizontal portion 40 of the lower arm of the lever 19, as shown, so that as the friction wheel presses upward against the brake as described, the raising of said brake simultaneously raises the said arm portion 33 and swings the lever 19 to 45 50 disengage the drive-disk 14 from the friction-wheel. Said link has its lower end threaded and extending loosely through an ear 34 projecting from the side of the lever 19, nuts 35, 36 on the threaded rod above and 55 below said ear providing for adjustment as to length of the link.

Obviously, if brake pressure were secured in some other way than by the link 32 which has been described, the lever 19 could 60 be operated by an adjustable dog 37 on the connecting rod 22 adapted to be engaged by a lug 38 on the hammer, and as a precaution such a dog is preferably provided in addition to the link 32, set so as to operate only 65 if the link for any reason should fail.

A second adjustable dog 39 on the connecting rod 22 is arranged thereupon to be engaged by the projecting lug 38 on the hammer 3 at the end of a downward stroke of said hammer and thus shift the drive-disk 13, 14 through the mechanisms just described to reverse the direction of rotation of the friction-wheel 5 and carry the hammer up again. In order to cushion the motion given to the connecting rod 22 by impact of the lug 38 with the dog 37 and insure uniform pressure of the drive disk against the friction-wheel 5, a spring 40 is arranged upon the upper end of the connecting rod 22, resting at its lower end upon a fixed collar on said connecting rod and pressing at its upper end against the lever arm 19, said lever arm and connecting rod having a slot-and-pin connection, so that the rod may have a little upward movement independent of the lever, except as transmitted by the spring. 70 75 80 85 90

As so far described, the machine is operated by lever 25, requiring one hand of the operator to hold the handle 27 down against gravitation of the weight 28 and keep the disk 13 in engagement with the wheel 5 to propel the hammer or head 3 downward. In order to leave both of the operator's hands free, however, I provide a treadle attachment so arranged that either it or the lever can be used, as desired. To this end I provide beneath the frame 1 a depending bracket 41 to which is pivoted a tripping member 42 preferably arranged and adapted to swing in substantially vertical plane, said tripping member having an arm 43 adapted to slidably operate a horizontally disposed detent 44. See Figs. 2 and 3. Said detent 44 is adapted to enter a notch 45 in a vertically slidable bar 46 to the upper end of which is attached a spring 47 under tension, so that when the detent 44 is withdrawn from the notch of the bar by swinging of said tripping member 42, the tension of spring 47 will draw said bar 46 upward. A lateral stud 48 on the lever 25 projects transversely through a slot 49 in said bar 46, so that the bar will engage said pin and raise the arm 24 of the lever when the bar 46 is released and drawn upward by said spring 47, and yet because of the slot the lever may be operated without movement of the bar when said bar is down. In order to release the said detent 44, the tripping member 42 has a second arm 50, forming with the arm 43 which slides the detent a bell-crank lever, and to this second arm 50 is connected a depending treadle 51 to receive the operator's foot. The rod 52 of said treadle has a lower guide bearing in an arm 53 of the bracket 41, and a spring 54 on said rod, between said arm and a fixed collar 55 on the rod, normally holds the treadle elevated and the detent 44 in locking position. 95 100 105 110 115 120 125 130

tion. Hence the machine can be started either by the foot treadle or by the hand lever.

It will be understood that when the machine has been started by means of the treadle 51, so that the weighted end of the lever 25 is held upward by the bar 46 and its spring 47, said weighted end will be depressed against the power of said spring at 10 the termination of a downstroke, by engagement of the lug 38 on the hammer with the dog 39 on the connecting rod, thus forcing the bar 46 downward so that it will be locked by the detent 44.

15 In order to secure automatically continuous operation of the press, instead of single strokes of the hammer, the tripping member 42 has a third arm 56, preferably projecting opposite to the second arm 50 in alinement therewith as shown, and which third arm is connected to the lever 25 by a link 57. This link at its lower end extends loosely through the arm 56 and is threaded to receive beneath said arm a nut 58 and lock nut 59 by which the length of the link can be adjusted so that it will be either operative or idle, according as continuous action of the press or a single stroke is desired. The upper end of the said link 57 constitutes an eccentric strap 60 extending around an eccentric 61 mounted on the outer end of the stud 48 on the lever 25 which projects through the slot 49 of the vertically spring-actuated bar 46, said eccentric having a handle 62 and providing means for quickly changing the length of the link 57. It will be understood that when the link 57 is sufficiently short, as shown in Fig. 4, the raising of the weighted end or arm 24 of the 20 lever 25 upon the return of the hammer to its highest position will pull upward on the third arm 56 of the tripping member 42 so as to release the detent 44 and start the hammer upon another stroke.

45 It is evident that as the point of contact between the friction wheel 5 and either of the drive disks 13 and 14 moves farther away from the shaft 7, the speed imparted to the descending hammer is increased and the force of impact or blow struck by the hammer is increased according to the square of the increase in speed. Thus when the hammer goes to the lowest possible point of its range of movement permitted by the machine, the heaviest blow will be struck, whereas if the work or lower die be raised and the lower dog 39 adjusted so that the hammer stops at a higher point, the force of impact or blow of the hammer will be decreased. In this way it is possible in my press to vary the blow of the hammer without changing the speed of the driving pulleys 10, 11, and to this end I provide fillers 63, one of which is shown in Fig. 4, any number of which may be employed to raise

the lower die 64 therein shown. It will be understood that these fillers 63 are preferably slotted at their edges, as at 65, to receive the bolts 66 which secure the lower die 64 to the bed 6 of the press as is common. Or if preferred the upper die could be lowered or brought nearer the bed 6 by inserting in the sliding head an auxiliary socket 67, of any desired length, as shown in Fig. 8, a set of these sockets being furnished with each press.

Having thus described the invention, what I claim is—

1. In a press, a frame, a screw mounted in said frame, a friction wheel fast on said screw and moving therewith, drive disks adapted to engage the edge of said friction wheel, and a brake located in the path of movement of the friction wheel and adapted to engage said friction wheel upon upward movement thereof.

2. In a press, a frame, a screw mounted in said frame, a friction wheel fast on said screw and moving therewith, drive disks adapted to engage the edge of said friction wheel, and a yielding brake located in the path of movement of the friction wheel and adapted to engage said friction wheel upon upward movement of the wheel.

3. In a press, a frame, a screw mounted in said frame, a friction wheel fast on said screw and moving therewith, drive disks adapted to engage the edge of said friction wheel, a brake adapted to engage said friction wheel upon upward movement thereof, and means connected to said brake for stopping the press.

4. In a press, a frame, a screw mounted in said frame, a friction wheel fast on said screw and movable therewith, drive disks adapted to engage the edge of said friction wheel, and a swinging brake projecting into the path of movement of the friction wheel and adapted to engage said friction wheel upon upward movement thereof.

5. In a press, a frame, a screw mounted in said frame, a friction wheel fast on said screw and movable therewith, drive disks adapted to engage the edge of said friction wheel, a swinging brake projecting into the path of movement of the friction wheel and adapted to engage said friction wheel upon upward movement thereof, and means connected to said swinging brake for stopping the press when the brake is swung.

6. In a press, a frame, a screw mounted in said frame, a friction wheel fast on said screw and moving therewith, drive disks adapted to engage the edge of said friction wheel, a slideable shaft for said drive disks, a brake adapted to engage said friction wheel upon upward movement thereof, and means connected to said brake for sliding said shaft.

7. In a press, a frame, a screw mounted in

- 5 said frame, a friction wheel fast on said screw and moving therewith, drive disks adapted to engage the edge of said friction wheel, a slideable shaft for said drive disks, 65 5 a lever adapted to slide said shaft, a brake adapted to engage said friction wheel upon upward movement thereof, and means connecting said brake to said lever.
8. In a press, a frame, a screw mounted 10 in said frame, a friction wheel fast on said screw and moving therewith, drive disks adapted to engage the edge of said friction wheel, a slideable shaft for said drive disks, 70 15 a brake adapted to engage said friction wheel upon upward movement thereof, a link connected to said brake, and means adapted to be operated by said link to slide the shaft.
9. In a press, a frame, a screw mounted in 20 said frame, a friction wheel fast on said screw and moving therewith, drive disks adapted to engage the edge of said friction wheel, a lever for controlling the transmission of power from said drive disk to 75 25 said friction wheel, a brake adapted to engage said friction wheel upon upward movement thereof, and a link connecting said brake to said lever.
10. In a press, a frame, a screw mounted in 30 said frame, a friction wheel on said screw, drive disks adapted to engage the edge of said friction wheel, a slideable shaft for said drive disks, a brake fulcrumed loose on said shaft and adapted to be engaged by the 80 35 friction wheel upon upward movement thereof, and means connected to said brake for sliding said shaft.
11. In a press, a frame, a screw mounted in said frame, a friction wheel on said screw, 40 drive disks adapted to engage the edge of said friction wheel, a slideable shaft for said drive disks, a lever adapted to slide said shaft, a yieldingly movable brake adapted to engage the friction wheel upon upward 85 45 movement thereof, and means connecting said brake to said lever.
12. In a press, a frame, a screw mounted in said frame, a friction wheel on said screw, drive disks adapted to engage the edge of 50 55 said friction wheel at opposite points, a shaft for said drive disks, a lever adapted to shift said shaft longitudinally, a controlling lever fulcrumed upon said frame at the base thereof, a connecting rod between said levers, a dog on said connecting rod, a lug carried by the screw adapted to engage said dog upon downward movement of the screw, a brake above the friction wheel adapted to be engaged and lifted thereby, and means 60 connecting said brake to said lever for sliding the shaft.
13. A press, a frame, a screw mounted in said frame, a friction wheel on said screw, drive disks adapted to engage the edge of 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895
- 5 said friction wheel, a lever for throwing one of said disks into engagement with the friction wheel and the other one out of engagement, a controlling lever fulcrumed upon said frame at the base thereof, a connecting rod between said levers, a dog on said connecting rod, means on the screw for engaging said dog upon downward movement of the screw, a bar adapted to slide up and down in said frame, a releasable detent adapted to hold said bar in lowermost position, a spring tending to draw said bar upward, and means for depressing said bar when the controlling lever is depressed and for raising said lever when the detent is released.
14. In a press, a frame, a screw mounted in said frame, a friction wheel on said screw, drive disks adapted to engage the edge of said friction wheel, a lever for throwing either of said disks into engagement with the friction wheel and the other out of engagement, a controlling lever fulcrumed upon said frame at the base thereof, a connecting rod between said levers, means normally holding said connecting rod 90 raised, a detent for holding said connecting rod depressed, means for releasing said detent, and means on the connecting rod adapted to be engaged when the screw is lowered to depress the controlling lever.
15. In a press, a frame, a screw mounted in said frame, a friction wheel on said screw, drive disks adapted to engage said friction wheel, a lever for throwing one of said disks into engagement with the friction 100 wheel and the other one out of engagement, a controlling lever fulcrumed upon said frame at the base thereof, a connecting rod between said levers, a weight adapted to depress said controlling lever, a vertically slideable bar having a slot adjacent to said lever, a spring for normally holding said bar elevated, a detent for holding said bar depressed, means for releasing said detent, and a stud projecting from the controlling lever into said slot of the bar and adapted to lie at the lower end thereof when the bar and lever are both depressed.
16. In a press, a frame, a screw mounted in said frame, a friction wheel on said screw, drive disks adapted to engage said friction wheel, a lever for throwing said disks into and out of engagement, a controlling lever fulcrumed upon said frame, a connecting rod between said levers, a bar having 115 a slot-and-pin connection with said lever and slidably mounted in said frame, means for sliding said bar, a detent for said bar, and means for operating said detent.
17. In a press, a frame, a screw mounted in said frame, a friction wheel on said screw, drive disks adapted to engage said friction wheel, a lever for throwing said disks into

and out of engagement, a controlling lever fulcrumed upon said frame, a connecting rod between said levers, a bar having a slot-and-pin connection with said lever and slidably mounted in said frame, a detent for said bar, a tripping member for operating said detent, and a treadle for operating said tripping member.

18. In a press, a frame, a screw mounted in said frame, a friction wheel on said screw, drive disks adapted to engage said friction wheel, a lever for throwing said disks into and out of engagement, a controlling lever fulcrumed upon said frame, a connecting rod between said levers, a bar having a slot-and-pin connection with said lever and slidably mounted in said frame, a bracket beneath said frame, a detent for said bar mounted in said bracket, a tripping member for releasing said detent mounted on said bracket, and a spring-controlled treadle also mounted on said bracket for operating said tripping member.

19. In a press, a frame, a screw mounted in said frame, a friction wheel on said screw, drive disks adapted to engage said friction wheel, a lever for throwing said disks into and out of engagement, a controlling lever fulcrumed upon said frame, a connecting rod between said levers, a bar having a slot-and-pin connection with the controlling lever and slidably mounted in the frame, a spring normally sliding said bar upward, a detent for said bar, a tripping member for releasing said detent, means connecting said tripping member and the controlling lever, and means on said connecting rod for depressing the same when the screw is lowered.

40 20. In a press, a frame, a screw mounted in said frame, a friction wheel on said screw, drive disks adapted to engage said friction wheel, a lever for throwing said disks into and out of engagement, a controlling lever fulcrumed upon the frame, a connecting rod between said levers, a bar having a slot-and-pin connection with the controlling lever and slidably mounted in the frame, a spring normally sliding said bar upward, a detent for said bar, a tripping member for releasing said detent, treadle means for operating said tripping member, means connecting said tripping member and the controlling lever to operate the member therefrom, and means on the

said connecting rod for depressing the same when the screw is lowered.

21. In a press, a frame, a screw mounted in said frame, a friction wheel on said screw, drive disks adapted to engage said friction wheel, a lever for throwing said disks into and out of engagement, a controlling lever fulcrumed upon the frame, a connecting rod between said levers, a bar having a slot-and-pin connection with the controlling lever and slidably mounted in the frame, a spring normally holding said bar upward, a detent for said bar, a tripping member for releasing said detent, a link connecting said tripping member and controlling lever, means for changing the effective length of said link, and means on the said connecting rod for depressing the same when the screw is lowered.

22. In a press, a frame providing a bed adapted to receive the work, a screw mounted in said frame, a friction wheel on said screw, drive disks in planes perpendicular to the plane of the friction wheel adapted to engage the edge of said friction wheel at opposite points, means for throwing said drive disks into and out of engagement with the friction wheel, a hammer carried by said screw, and means for varying with any given piece of work the distance of the point of engagement of said friction wheel with each drive disk from the center of said drive disk at the moment of impact of the hammer with said work.

23. In a press, a frame providing a bed adapted to receive the work, a screw mounted in said frame, a friction wheel on said screw, drive disks in planes perpendicular to the plane of the friction wheel adapted to engage the edge of said friction wheel at opposite points, means for throwing said drive disks into and out of engagement with the friction wheel, a hammer carried by said screw, and means for raising and lowering a given piece of work on said bed and thus varying the distance of the point of engagement of said friction wheel with each drive disk from the center of said drive disk at the moment of impact of the hammer with said piece of work.
